WARREN H. COWDERY, OF CLEVELAND, OHIO, ASSIGNOR TO THE AMERICAN FORK AND HOE COMPANY, OF CLEVELAND, OHIO, A CORPORATION OF OHIO.

METHOD OF MAKING SPADES.

1,360,892.

Specification of Letters Patent. Patented Nov. 30, 1920.

Application filed July 31, 1918. Serial No. 247,501.

To all whom it may concern:

Be it known that I, WARREN H. COWDERY, a citizen of the United States, and a resident of Cleveland, county of Cuyahoga, State of Ohio, have invented a new and useful Improvement in Methods of Making Spades, of which the following is a specification, the principle of the invention being herein explained and the best mode in which I have 5 contemplated applying that principle, so as to distinguish it from other inventions:

The present invention, relating, as indicated, to a method of making spades and similar articles, is directed toward an improved method of manufacturing the metal portion of a spade or like article, without the necessity of adding or fastening thereto any such strip as is usually riveted or bolted across the head of the spade to serve as a 10 foot rest. The common spade is usually provided with a short strip of metal extending transversely across the head of the spade and fastened by riveting or otherwise to the body of the spade proper, and this of course necessitates a separate formation of these 15 strips and several operations in fastening the same to the spade. Not only is the present method more economical than the ones heretofore in use, but the article as thus 20 manufactured is distinctly superior and has no parts which can become unfastened from the spade proper. To the accomplishment of the foregoing and related ends, said invention, then, consists of the means herein- 25 after fully described and particularly pointed out in the claims.

The annexed drawing and the following description set forth in detail one method and one product exemplifying my invention, 30 such disclosed procedure and product constituting, however, but one of the various applications of the principles of my invention.

In said annexed drawing:—

Figure 1 is a plan view of a flat part of stock from which the spade blanks are cut or stamped, the lines of cutting and hence the form of the blanks being indicated in this figure; Fig. 2 is a transverse sectional 45 view of forming rolls in operation upon a previously stamped-out blank; Fig. 3 is a similar view showing slightly different rolls for producing a modified type of spade, both of Figs. 2 and 3 being more or less diagrammatic; and Figs. 4 and 5 are transverse sec-

tions through the head of the spades formed respectively by the rolls of Figs. 2 and 3.

As indicated in Fig. 1 the spade blanks are stamped from a rectangular relatively thin sheet or bar of stock 1, the blanks being stamped out in an interlocked relation, and each blank consisting of a rectangular portion 2 and a shank portion 3, extending at right angles to the longest dimensions of the body portion and transversely of the strip of stock.

In my improved method of manufacture I first cut out the blanks and then thin the body portion of the spade from the head end to the lower end or edge of the spade 50 by means of rolls 4 and 5, shown in Fig. 2, which are provided with extending portions 6 and 7, respectively. The outer surfaces of these extending portions are not formed concentrically about the axis of the rolls, but 55 are formed like cams, so that the ends of the two extensions, which are shown at the right of Fig. 2 are closer together when in contact with the spade 8, than are the two portions 9 and 10, which are shown in this 60 figure as in actual contact with the head portion of the spade. The eccentricity of the extensions 6 and 7 is of course gradual, and is so arranged that the spade 8 is gradually tapered from a relatively slight thickness at the edge 11 to a greater thickness at the portion 12, while the extensions are formed in unequal lengths, so that the end 9 of the extension 6 will leave the head 12 65 of the spade before the end 10 of the extension 7 does, and in this way forces the metal 70 which has been rolled from the body of the spade to the upper end into a transversely extending shoulder 13 of some width. This shoulder 13 is shown in transverse section 75 in Fig. 4. After the blade of the spade has thus been graduated as to its thickness throughout its length the spade is hammered or otherwise forged into the proper 80 shape, that is, it is formed slightly concave 85 transversely, and the shank portion 3 is formed as may be desired to fit into a furrow which may engage the handle to be attached to the spade.

In Fig. 3 I have shown rolls 14 and 15 90 respectively, which operate similarly to thin out the body portion 8 of the blank, but these rolls terminate at the same point against the body of the spade, and thus produce oppositely extending shoulders 18, as 95

better shown in Fig. 5. Otherwise the action of the rolls 14 and 15 is identical in function with the operation of the rolls 4 and 5, which I have previously described, and 5 the subsequent treatment of the partially formed spade blank is also the same.

By thus utilizing the metal which is rolled from one end of the spade to the other for the formation of a broadened head for the 10 spade body, I have found it possible to make this head edge of sufficient width to serve as a foot rest or support, which is as satisfactory as the fastened support and is much more economically made. An added 15 advantage is that the present foot rest is an integral part of the spade body and does not have to be fastened on during the manufacture and cannot come loose during the use of the spade, no matter how severe is this 20 use.

Other forms may be employed embodying the features of my invention instead of the one here explained, change being made in the form or construction, provided the

elements stated by any of the following 25 claims or the equivalent of such stated elements be employed, whether produced by my preferred method or by others embodying steps equivalent to those stated in the following claims.

I therefore particularly point out and distinctly claim as my invention:—

1. The method of making spades which consists in rolling a spade blank longitudinally to force the metal therein to flow toward the head end, and forcing some of such metal laterally to form a flange along the head end of such spade blank.

2. The method of making spades which consists in rolling a spade blank longitudinally between eccentric rolls to force the metal therein to flow toward the head end, and forcing some of such displaced metal laterally to form a flange along the head end of such spade blank.

Signed by me, this 26 day of July, 1918.

WARREN H. COWDERY.
